AIR CIRCULATING HEATER

Clarence R. Graham, Palo Alto, Calif., assignor
to James Graham Manufacturing Co., San
Francisco, Calif., a corporation of California

Application June 20, 1936, Serial No. 86,312

3 Claims. (Cl. 257—139)

This invention relates generally to circulating air heaters, such as are employed for heating dwellings or rooms. In one embodiment of the invention described herein, the heater is incorporated with a gas cooking range.

It is an object of the invention to provide a heater of the above character, characterized by a simple and efficient type of heating unit. This heating unit is provided with fins or ribs for more effectively transferring heat to convecting currents of air, but the construction is such that these fins are integral with sheet metal walls, thus providing more effective conduction of heat to the same, and eliminating welding operations.

Further objects of the invention will appear from the following description in which the preferred embodiments of the invention have been set forth in detail, in conjunction with the accompanying drawings.

Referring to the drawings:

Fig. 1 is a front elevational view of a gas range, incorporating an air circulating heater in accordance with the present invention.

Fig. 2 is an end view of the range illustrated in Fig. 1.

Fig. 3 is a cross-sectional detail taken along the line 3—3 of Fig. 2.

Fig. 4 is a side elevational view of the heating unit incorporated in the air circulating heater provided in the gas range of Figs. 1 to 3 inclusive.

Fig. 5 is a cross-sectional detail taken along the line 5—5 of Fig. 4.

Fig. 6 is a cross-sectional detail taken along the line 6—6 of Fig. 4.

Fig. 7 is a front elevational view, showing my air circulating heater incorporated in a range from which a trash burner box has been omitted.

Fig. 8 is a cross-sectional detail similar to Fig. 3.

Referring first to Figs. 1 to 3 inclusive, I have shown a range of the cabinet type, which in this instance is adapted to use natural or artificial gas as a source of fuel. The closed top 10 of the cabinet 11, forms the cooking surface. The cabinet can be provided with oven and broiler compartments, closed by the doors 12 and 13, utility drawers 14, and also in this instance a trash burner box 16. The trash burner box is disposed below one portion of the cooking surface 10, and adjacent the upright end wall 17.

Formed within the cabinet, and adjacent the outwardly bulged end wall 17, there is an air heating chamber 18. Chamber 18 is formed in

part by an upright wall portion 19, an inclined wall portion 20, and upright wall portion 21, the last named wall being disposed between the trash burner box 16, and the upper part of the end wall 17. The front and rear sides of chamber 18 are closed by suitable sheet metal walls, which may be the conventional front and rear walls of the cabinet. The end wall 17 is provided with upper and lower grill openings 23 and 24, to permit air from the room to flow into chamber 18, and then out through the upper grill opening 23, after being heated.

The gas heating unit 25, disposed within the compartment 18, can be best explained by reference to Figs. 4 to 6 inclusive. It consists of a pair of spaced upright side walls 26, joined together by the upper curved wall portion 27. Disposed upon the outer faces of the walls 26 are the heat transferring fins or ribs 28. All of the parts of the heating unit just described, are made 20 from one single piece of sheet metal. Thus a sheet of metal is first provided with parallel corrugations, to provide substantially U-shaped fins, as illustrated in Fig. 6. For a medial portion of this piece of sheet metal, which subsequently forms the wall portion 27, the fins or corrugations are flattened down upon the sheet of material, to form flattened folds, as indicated at 29. After this operation the sheet metal is bent over a suitable mandrel, to form the curved 30 wall portion 27.

The ends of the heating unit are closed by walls 31, whereby the interior of the unit forms a space or path 32, for flow of hot products of combustion. Near the upper part of the unit, 35 one of the end walls 31 is provided with a vent opening 33, adapted to be connected to a flue. In order to provide a smoother and properly distributed flow of products of combustion, a baffle wall 34 can be provided, this wall having 40 spaced openings 36 through which the products of combustion may flow. The lower edges of walls 26 can be reinforced by metal straps 37, and brackets 38 and 39 can be provided, for properly mounting the unit within the chamber 18.

Fig. 3 illustrates a gas burner 41, disposed at the lower end of the heating unit. Fig. 2 illustrates connection between the vent opening 32, and a flue pipe 42.

The space within the cabinet occupied by the trash burner box 16, and also by the air circulating heater described above, can be segregated from the remainder of the cabinet by the partition wall 43. Thus a space 44 is provided between 55

partition 43 and the wall 19, for receiving the ash tray 46. Access to the front end of the heating unit can be accommodated by a door 47, on the front of the cabinet. Likewise another door 49 can be provided, to permit access to the grate bars of the trash burner box. The forward end wall of the heating unit can be provided with a flame inspection window 51, and also with an opening 52, for lighting a pilot burner.

10 Operation will be apparent from the above description. When the burner 41 is in operation, heated air from the compartment 18 circulates upwardly and flows out through the grill openings 23, and cooler air is drawn into the lower grill openings 24. The heating unit effectively transfers heat to the convection currents of air, and no buckling or cracking noise will be experienced when the burner is starting in operation, or after the burner is extinguished, because of the reinforcing action of the corrugations 28.

15 The modification shown in Figs. 7 and 8 differs from that described above, in that the trash burner box has been omitted. Thus in this case the compartment 53, in which the heating unit 25 25 is disposed, is in part disposed below the space 54, occupied by the burners 56 of the range. The end wall 57 likewise has upper and lower grill openings 58 and 59, for circulation of air to be heated.

20 30 I claim:

1. In an air heater, a pair of spaced upright side walls, an upper wall serving to join the up-

per edges of the side walls, all of said walls being formed of one continuous piece of sheet metal, the space between said walls serving as a flow path for hot products of combustion, and corrugations formed in said walls, said corrugations forming a series of fins on the outer faces of said side walls and being flattened to form folds in said upper wall. 5

2. In an air heater, a pair of spaced upright side walls, an upper wall serving to join the upper edges of the side walls, all of said walls being formed of one continuous piece of sheet metal, the space between said walls serving as a flow path for hot products of combustion, and a series of parallel corrugations formed in said walls, said corrugations forming spaced upright fins extending outwardly from the side walls and being flattened to form compact folds in said upper wall. 10

3. In an air heater, a pair of spaced upright side walls, an upper wall serving to join the upper edges of the side walls, all of said walls being formed of one continuous piece of sheet metal, the space between said walls serving to form a flow path for hot products of combustion, and a series of parallel corrugations formed in said walls, said corrugations forming U-shaped fin sections extending outwardly from the side walls, and being flattened to form compact folds in said upper wall. 20 25 30

CLARENCE R. GRAHAM.
